Attorneys

UNITED STATES PATENT OFFICE.

ALBERT F. EMMONS, OF PITTSBURGH, PENNSYLVANIA.

POLE-LINE INSULATOR.

Application filed August 27, 1920. Serial No. 406,312.

To all whom it may concern:

Be it known that I, ALBERT F. EMMONS, a citizen of the United States, and resident of Pittsburgh, in the county of Allegheny and State of Pennsylvania, have invented a new and useful Improvement in Pole-Line Insulators; and I do hereby declare the following to be a full, clear, and exact description thereof.

10 My invention relates to pole-line insulators and it has for its object to provide an improved insulator which I term a "Lock insulator" and in which the use of the ordinary glass insulators, wood pins, bolts and 15 tie-wires shall be entirely eliminated.

Another object of my invention is to produce an improved pole-line insulator which may be constructed either as a separate attachment for ordinary pole-line cross-arms 20 or as an integral part of the cross-arm itself. In the latter case the entire cross-arm is made of suitable insulating material.

In the accompanying drawing Fig. 1 is a perspective view of one end of a pole-line cross-arm provided with a set of insulators constructed in accordance with my invention; Fig. 2 is a side elevational view of a portion of the cross-arm shown in Fig. 1, showing one of the insulators; Fig. 3 is 25 a plan view of the construction shown in Fig. 2; Fig. 4 is a plan view similar to Fig. 3 showing the lock portion of the insulator with the key removed; Fig. 5 is an inverted plan view of the key portion of the insulator; Fig. 6 is a longitudinal vertical 30 sectional view taken centrally through the assembled insulator; and Fig. 7 is a transverse vertical sectional view, the section being taken substantially along the line 7—7, 40 Fig. 2.

As shown in the drawing, my improved insulator consists of four parts, a base or lock portion 2, a key portion 3, a wire-holding pin 4, and a locking preferably tapered pin 5. The lock portion 2 may be composed of glass or of any other suitable insulating material such, for example, as molded material containing phenolic condensation products, or such other material 45 as may be found desirable. When the lock portion of the insulator is made integral with the cross-arm, the entire cross-arm is constructed of the insulating material selected. I have found that the inorganic

insulating material known as "marvelite" 55 is well adapted for this purpose.

The lock portion 2 of the insulator, when made as a separate article of manufacture as shown in the drawing, is of generally rectangular shape and is provided on its upper side with a recess to receive the key 3. This recess has one end cut squarely into the body of the lock as shown at 6, while its other end is undercut as shown at 7. The overhanging ledge formed by the undercut wall 7 of the recess is cut away in semi-circular form as shown at 8 on Fig. 4 and directly beneath this cut-away portion is an opening which receives the pin 4. This pin has a flange or shoulder 10 at its upper edge 70 which forms a seat for the wire 11. The wire enters the lock through an opening 12 formed adjacent to the undercut wall 7, passes around the pin 4, and is brought out through another opening 12 on the opposite 75 side of the lock.

The key 3 is so shaped as to conform to the recesses formed in the lock as described above. It consists of a body portion 15 having a projection 16 which fits within the semi-circular recess 8 in the lock and the body portion 15 is cut away as shown at 17 to fit over the pin 4 and the curved part of the wire 11. The upper portion 19 of the key is rounded and extends beyond 80 the body portion 15 on all sides, forming a flange 20 which covers the joints between the lock and the key and serves to keep out moisture. The lock and the key are provided with matched grooves 21 which together 85 form a seat to receive the locking pin 5.

Each insulator may be placed on top of the cross-arm 21^a or in a recess cut in the top of the cross-arm, and is fastened in 90 position by means of lag-screws 22 which extend through the lock portion 2 and into the cross-arm.

The locks 2 are secured to the cross-arm before the cross-arm is placed in position on the pole. When the wires are to be attached, the lineman crimps the wire with a suitable tool to produce a semi-circular loop, and places the loop in position with its ends extending through the openings 12, inserts the pin 4, places the key in the lock, and finally secures the key in position by inserting the pin 5. It will be observed that 100 105

the lineman is not required to fasten the wires in place by means of tie-wires as in the ordinary pole-line insulators and that the assembly of each insulator is made quickly and permanently.

If desired, the pin 5 may be made in the form of a bolt, in which case the lineman completes the assembly by screwing a nut on the end of the bolt. As a further precaution against removal of the key, the key and the lock may be provided, as shown in Fig. 6, with openings to receive a lag screw 23. This screw, however, is not necessary since the lock and the key are held firmly together by means of the pin 5.

It is to be understood that the details of construction which I have herein shown and described may be modified in various respects without departing from my invention and I therefore desire that no limitations be imposed upon my invention except such as are indicated in the appended claims.

I claim as my invention:

1. A pole-line insulator comprising a lock member provided with a recess having one squarely cut end and one beveled end, and provided also with an opening communicating with said recess, a wire-engaging pin received in said opening, a key member shaped to fit within the said recess and over the said pin, and a locking pin received in registering grooves in the said lock and key members.

2. A pole-line insulator comprising a lock member provided with a recess having one squarely cut end and one undercut beveled end, and provided also with an opening at the undercut beveled end of said recess, a wire-engaging pin received in said opening, a key member shaped to fit within said recess and over the said pin, and a locking pin received in registering grooves in the said lock and key members.

3. A pole-line insulator comprising a lock member having a recess extending from side to side thereof, the said recess having one squarely cut end and one undercut beveled end, a pin received in an opening formed in said lock member, said pin extending into said recess, a key member shaped to fit within said recess and over said pin, the said members being provided with openings cooperating to define a channel for receiving a loop of wire adjacent to the said pin, and a locking pin received in matched grooves formed in said lock and key members.

4. A pole-line insulator comprising a lock member of generally rectangular form having a recess extending across its upper face, said recess having one squarely cut end and one undercut beveled end, and having a semi-circular recess at the said beveled end of the said first-named recess, a pin received in an opening in said lock member beneath said semi-circular recess, said pin being provided with a flange at its upper end, and the said lock member being provided with wire-receiving openings adjacent to said pin, a key member shaped to fit within said recesses in said lock and over said pin, said key member having a curved wall cooperating with said wire-receiving openings and said flange to define a channel for receiving a loop of wire, the said key member being provided with an overhanging or roof flange, and a locking pin received in registering grooves formed in said lock and key members at the said squarely cut end of said first-named recess.

In testimony whereof, I, the said ALBERT F. EMMONS have hereunto set my hand.

ALBERT F. EMMONS.
